UNITED STATES PATENT OFFICE

150,482

DESIGN FOR A VACUUM COFFEE MAKER

Harry Wohl, Chicago, Ill., assignor to Nicro Steel
Products, Inc., Cook County, Ill., a corporation
of Illinois

Application February 28, 1947, Serial No. 137,234

Term of patent 14 years

(Cl. D44—26)

To all whom it may concern:

Be it known that I, Harry Wohl, a citizen of the United States, residing at Chicago, in the county of Cook and State of Illinois, have invented a new, original, and ornamental Design for a Vacuum Coffee Maker, of which the following is a specification, reference being had to the accompanying drawing, forming a part thereof.

Fig. 1 is a top plan view of the coffee maker embodying the new design.

Fig. 2 is a side elevational view showing the coffee maker in operation.

Fig. 3 is a section taken on line 3—3 of Fig. 2 showing the pouring lip of the lower vessel.

Fig. 4 is a top plan view of the lower vessel with lid in position.

Fig. 5 is a side elevational view of lower vessel.

Fig. 6 is a front view of the lower vessel showing spout formed by dispensing lip and lid.

I claim:

The ornamental design for a vacuum coffee maker, substantially as shown.

HARRY WOHL.
